UNITED STATES PATENT OFFICE.

MATTIS LUNDBOM, OF ÖREBRO, SWEDEN.

STRETCHER, SICK-BED, AND THE LIKE.

1,344,088.

Specification of Letters Patent. Patented June 22, 1920.

Application filed September 11, 1918. Serial No. 253,655.

To all whom it may concern:

Be it known that I, MATTIS LUNDBOM, a subject of the King of Sweden, residing at Örebro, in the Kingdom of Sweden, have invented a new and useful Improvement in Stretchers, Sick-Beds, and the like, of which the following is a specification.

The present invention relates to an improvement in stretchers, sick-beds and the like. One of the objects of the invention is to render it possible to use and to move the stretcher or bed directly on rail tracks of different gages as used at present in hospitals. A further object is to render it possible to place and to transport stretchers and beds of varying breadths and of otherwise different constructions in ordinary hospital wagons, for instance motor ambulances, independently of the construction of the floor or the part of the wagon supporting the stretcher. Similar devices as heretofore used are often encumbered with the disadvantage that stretchers or beds which are not exactly dimensioned to suit, that is to say do not belong to the wagon, cannot be transported in the same. In the ordinary motor ambulances, for instance, there is often a recess in the floor for storing various loose fixtures of the wagon, and the stretcher is placed over this recess with its legs resting on the floor at each side of the recess. If another stretcher than the one dimensioned for use in the ambulance must be placed in the same, the stretcher is very often narrower than the recess in the floor, and its legs can thus not gain support from the floor of the ambulance. This disadvantage is often encountered for instance when transferring stretchers or beds from railway ambulance carriages to motor ambulances. The said disadvantage is avoided according to the present invention.

The present improvement consists mainly in this that the legs of the stretcher or the bed are adjustable relatively to the stretcher or bed toward and away from one another in the transverse direction of the stretcher or the bed. The legs may be adjustably secured directly to the stretcher or the bed, or they may be adjustably secured to a frame piece about corresponding to the width of the stretcher or the bed and provided with means for being secured to the stretcher or the bed. By adjusting the distance between the legs they may thus be

made to suit the tracks in the hospitals, and by adjusting the legs so that the distance between the same becomes greater than the width of the recess in the floor of the motor ambulance the stretcher or the bed may thus be placed on the floor of the ambulance.

In the accompanying drawing an embodiment of the invention is shown by way of example in which embodiment the legs are adjustably secured to a frame piece to be secured to the stretcher or the bed. Figure 1 shows an end view of the device, Fig. 2 a plan view, and Fig. 3 a side view. Fig. 4 shows a detail of modification.

The device illustrated in the drawing consists of a frame piece 1 which fits the end of an ordinary stretcher or sick-bed and may be secured to the same by means of straps 2 on the frame piece, two of said straps being shown in engagement with the sides and two being shown in engagement with the end of the frame 3 of the stretcher or the bed, which frame is indicated by dot and dash lines in the drawing. In the straps 2 engaging the end of the frame 3 there are provided pins 4 which secure the stretcher frame to the frame piece. On the lower side of the frame piece along its end, that is to say in the transverse direction of the stretcher, there are sliding arms 5 which are guided in sleeves 6 and are secured in their different positions by means of screws 7 secured to the frame piece and projecting through elongated slots 8' in the arms 5. In the embodiment shown these arms are made in one piece with the legs 8. Between the legs 8 and the frame piece there are stays 9 the lower ends of which are pivotally connected with sleeves 10 rotatable on the legs, and the upper ends of the stays are adjustably connected with the frame piece by means of screws 11 projecting through elongated slots 12 in the stays.

The device above described is preferably stored, that is to say kept in readiness in every hospital, hospital wagon or motor ambulance, and if the device is to be used it is only necessary to introduce the end of the stretcher or the bed into the straps 2 of the frame piece and to insert the pins 4 in their places, when the frame piece 1 is securely fastened to the stretcher. By loosening the wing-nuts 13 and 14 the arms 5 and the legs 8 may be freely adjusted so that the legs may be placed on the rail track in the

- hospital or on the floor of the ambulance on either side of the recess in the same. They are, of course, fixed in the adjusted position by tightening the nuts 13 and 14.
- 5 The legs 8 thus having been adjusted the legs of the stretcher or the bed may suitably be folded up, if they are foldable as is usually the case, or the legs 8 may be made so much longer than the legs of the 10 stretcher or the bed that these latter do not in any case reach the floor when the stretcher is supported by the legs 8. These legs may preferably be made resilient as indicated in Fig. 1. The legs 8 are preferably provided with casters in order to 15 facilitate the pushing-in of the stretcher on the floor of the wagon and the moving of the stretcher on the rail track in the hospital.
- 20 As shown in Figs. 1 to 3 the device is adapted for stretcher frames made of tubes, but the device may obviously also be attached to other bed frames, in which case the straps 2 are preferably made adjustable 25 so as to be capable of adjustment for different thicknesses of the frames. Fig. 4 illustrates a strap 2 sliding up and down in a sleeve 15 secured to the frame piece 1 in which sleeve the strap may be secured by 30 means of a set-screw 16.

For supporting a stretcher or a bed it is in many cases sufficient to use only one frame piece as shown in the drawing, but it is obvious that two such frame pieces may 35 also be used, one at each end of the stretcher. It will be obvious to those skilled in the art that these frame pieces may also be so connected that they form a single frame piece on which the stretcher or the bed may be 40 placed, and further, that although in the embodiment described above and illustrated in the drawings the legs are adjustably secured to a frame piece to be fastened to the stretcher or bed, the invention is not limited 45 to this construction, but that it is also possible in similar manner to secure the legs adjustably directly to the stretcher or the bed.

I claim:

- 50 1. The combination with a stretcher hav-

ing a rigid frame of legs removably secured to said frame and adjustable relatively thereto toward and away from one another in the transverse direction of the stretcher.

2. In a stretcher, the combination of a 55 stretcher frame, a frame piece about corresponding to the width of said stretcher frame, means for securing said frame piece to said stretcher frame, members movable in the transverse direction of said stretcher 60 frame along the portion of said frame piece corresponding to the end of said stretcher frame, means on said frame piece for guiding said members, legs secured to said members, and stays between said legs and said 65 frame piece.

3. In a stretcher, the combination of a stretcher frame, a frame piece of a shape corresponding to the end and adjacent portions of the sides of said stretcher frame, 70 straps on said frame piece gripping the end and adjacent portions of the sides of said stretcher frame, means for locking said stretcher frame into said straps, members movable toward and away from one another in the transverse direction of said 75 stretcher frame along the portion of said frame piece corresponding to the end of said stretcher frame, means on said frame piece for guiding said members, means for securing said members to said frame piece in adjusted positions, legs secured to said members, sleeves rotatable on said legs, stays hinged to said sleeves, and means for adjustably securing said stays to the portions 80 of said frame piece corresponding to the sides of said stretcher frame.

4. In a stretcher, the combination of a stretcher frame, a frame piece about corresponding to the width of said stretcher frame, 90 adjustable means for securing said frame piece to said stretcher frame, members movable in the transverse direction of said stretcher frame along the portion of said frame piece corresponding to the end 95 of said stretcher frame, means on said frame piece for guiding said members, legs secured to said members, and stays between said legs and said frame piece.

MATTIS LUNDBOM.
